UNITED STATES PATENT OFFICE.

JOHN ROY HUNT, OF INDIANAPOLIS, INDIANA, ASSIGNOR TO INTERNATIONAL MOVING PICTURE & FILM COMPANY, OF NASHVILLE, TENNESSEE, A CORPORATION.

MACHINE FOR PROJECTING COLORED MOTION PICTURES.

1,404,773.

Specification of Letters Patent.

Patented Jan. 31, 1922.

Original application filed June 16, 1919, Serial No. 304,686. Divided and this application filed September 27, 1919. Serial No. 326,723.

To all whom it may concern:

Be it known that I, JOHN ROY HUNT, a citizen of the United States, and a resident of Indianapolis, county of Marion, and State of Indiana, have invented a certain new and useful Machine for Projecting Colored Motion Pictures; and I do hereby declare that the following is a full, clear, and exact description thereof, reference being had to the accompanying drawings, in which like numerals refer to like parts.

The object of this invention is to improve the construction and operation of means for projecting colored motion pictures, and particularly means for guiding and exactly locating the film in its movement and the aperture plate so that the pictures will always accurately register with the aperture. This is of vital importance in machines of this type where two pictures are simultaneously projected through two apertures and superimposed upon each other upon the screen. Unless the parts are absolutely accurate, there will not be accurate and definite presentation of the pictures on the screen.

This application is a division from my application filed June 16, 1919, Serial No. 304,686 on a machine for projecting colored moving pictures.

The full nature of this invention will be understood from the accompanying drawings and the following description and claims.

In the drawings Fig. 1 is a rear elevation of the feeding, tracking and aperture mechanism in a machine of the kind, with a film gate, with the lower aperture in open position. Fig. 2 is a side elevation of what appears in Fig. 1 with a portion shown in a vertical section on line 2-2 of Fig. 1. Fig. 3 is a rear elevation of an aperture plate. Fig. 4 is a horizontal section on the line 4-4 of Fig. 1, but showing the film therein in cross section. Fig. 5 is a section on the line 5-5 of Fig. 3, but on a larger scale.

The invention herein set forth has been made for use in a machine for projecting colored motion pictures where the pictures are arranged out of the natural sequence. There are two projecting apertures, an upper aperture 10 and a lower aperture 11, and means for feeding the film 12 alternately or intermittently to said apertures.

As seen in Fig. 1 there is a tracker plate 55 13 which carries aperture plates 14 and 15 for the upper and lower apertures 10 and 11. The aperture plates 14 and 15 are adjustably mounted by the screws 16, which extend through eccentric holes 17 in the plates 14 and 15, so that by screwing in the lower screws and loosening the upper screws, or the reverse, the plate 14 can be vertically adjusted and by said screws, the plate 14 can be adjusted laterally, diagonally 65 or longitudinally.

The aperture plates 14 and 15 are spaced some distance apart so as to adapt the apertures for projecting the pictures of the different series in their natural sequence or 70 order, as will hereafter be explained. There is the usual construction of film gates, one for each aperture and the film 12 passes down between the film gates and the aperture plates 14 and 15. Associated with the 75 tracker plate there is a pilot tension sprocket 18 above each aperture and an intermittent feed sprocket 19 below each aperture, as shown in Fig. 1. Each sprocket has a stationary flange 20 on its left-hand end and 80 a laterally movable flange 21 on its right-hand end which is under tension by reason of a spring 22 surrounding the sprocket shaft and which forces the flange against the edge of the film yielding according 85 to the tension of the spring which is adjustable by reason of a nut 23 on the threaded end of a sprocket shaft 24. This affords an accurate means for guiding the film as it passes over the sprockets so that it will 90 have absolutely no lateral play or movement. The film is further guided for the sake of absolute accuracy by the following means:

There are vertical tracker strips 25 on the plate 13 at each side of the aperture, as 95 shown in Fig. 4, upon which the film travels. One edge of the film as it travels engages and is guided by the vertical guide bar 26 and the other edge of the film is guided by the extra flanges 27, two of which are provided in association with each aperture, the flanges 27 for the lower aperture being shown in the lower part of Fig. 1, while said flanges for the upper aperture are hidden by the film gate 28. These flanges 105 27 press and hold the film laterally against the guide bars 26 and cause absolutely accurate travel of the films over the apertures.

The flanges 27 are slidable on transversely arranged pins or rods 29 secured to the plate 13 and they are pressed laterally by a spring 30 and the tension thereof is adjusted by the 5 nuts 31. The flanges 27, therefore, cooperate not only with the guide bars 26 but with the flanges 21 of the feed sprockets.

The gate 28 is hinged at 32, see Fig. 4, to brackets 33 secured to the plate 13 and it 10 is held in closed position as shown in the upper parts of Figs. 1 and 2, and in Fig. 4, by a latch 34 that is pivoted on plate 13.

The film gate carries a tension shoe 35, as shown in Figs. 1 and 4, and which is pressed 15 into engagement with the film by a spring construction 36.

The invention claimed is:

1. A machine for projecting motion pictures, including a plurality of apertures, 20 tracker strips over which the film passes having at one side a guide bar to be engaged by and guide one edge of the film, and flanges yieldingly mounted in connection with the tracker strip at the other side of the 25 film adapted to engage said side of the film and thereby hold the film securely in place.

2. A machine for projecting motion pictures, including a plurality of apertures, tracker strips over which the film passes having at one side a guide bar to be engaged 30 by and guide one edge of the film, a pin projecting laterally below the tracker strip beyond the other side thereof, a flange slidably mounted on said pin in position to engage the other edge of the film, and a 35 spring on said pin for forcing the flange against the film and a nut for adjusting the tension of the spring.

3. A machine for projecting motion pictures, including a plurality of apertures, a 40 tracker strip located on each side of each aperture for guiding the film, a stationary guide bar connected therewith for guiding one edge of the film, and yieldingly mounted flanges above and below said aperture for 45 engaging the other edge of the film for holding the film securely in place at the aperture.

In witness whereof, I have hereunto affixed my signature.

JOHN ROY HUNT.
